STREET LIGHTING LUMINAIRE

Donald William Harling, Milwaukee, Wis., assignor to McGraw Electric Company, Milwaukee, Wis., a corporation of Delaware

Application April 29, 1950, Serial No. 9,579

Term of patent 14 years

(Cl. D48—31)

To all whom it may concern:

Be it known that I, Donald W. Harling, a citizen of the United States, residing at Milwaukee, in the county of Milwaukee and State of Wisconsin, have invented a new, original, and ornamental Design for Street Lighting Luminaires, of which the following is a specification, reference being had to the accompanying drawing, forming a part hereof.

In the drawing:

Fig. 1 is a perspective view of a street lighting luminaire, showing my new design.

Fig. 2 is a side elevational view of the luminaire.

Fig. 3 is a front elevational view of the luminaire; and

Fig. 4 is a top plan view thereof.

The dominant features of my design reside in that portion shown in full lines in the drawing.

I claim:

The ornamental design for a street lighting luminaire, as shown and described.

DONALD WILLIAM HARLING.
